(57) **CLAIM**

The ornamental design for a shoe rack, as shown and described.

DESCRIPTION

FIG. 1 is a perspective view of my new design, comprising a shoe rack;

FIG. 2 is a top plan view thereof;

FIG. 3 is a front elevation view thereof, the back elevation view being identical thereto;

FIG. 4 is right side elevation view thereof, the left side elevation view being the mirror image thereof; and,

FIG. 5 is a bottom plan view thereof.
